UNITED STATES PATENT OFFICE.

BENAIAH G. JAYNE, OF NEW YORK, N. Y., ASSIGNOR TO IDANHA MACHINE COMPANY, A CORPORATION OF NEW YORK.

GOLD-WASHER.

No. 855,640.

Specification of Letters Patent.

Patented June 4, 1907.

Application filed April 2, 1906. Serial No. 309,366.

To all whom it may concern:

Be it known that I, BENAIAH G. JAYNE, a citizen of the United States, residing at New York, in the county of New York and State 5 of New York, have invented certain new and useful Improvements in Gold-Washers, of which the following is a specification.

My invention relates to gold washers, and has for its object the improvement of the apparatus of like nature and purpose shown in my application for Letters Patent of the United States, filed July 27, 1905, Serial No. 217,447.

The particular features of construction constituting my present invention are illustrated in the accompanying drawings, of which

Figure 1 represents a side view of a tank with portions of one side broken away to disclose interior parts. Fig. 2 is a cross-section of one of the jet tubes, and is taken on the line *a—a* of Fig. 3, which figure shows a top plan view of the head of a jet tube, and exhibits the jet slots upon both sides of the partition of the tank. Fig. 4 is a section of one of the heads having an inclined jet slot. Fig. 5 represents a cross-section of the tank shown in Fig. 1. Fig. 6 is a plan view from above the tank. Fig. 7 is a fragmentary side view of one wing showing, on an enlarged scale, two vanes and the parts by which the pivoted ends of the vanes are operated. Fig. 8 is a cross-section of a modification, showing the wings and partition secured together and adapted to be raised and lowered within the tank.

Like numbers are used to refer to the same parts throughout.

From a main service pipe or manifold 1, a 40 row of jet tubes 2 extend upwardly and are secured in the bottom of a tank 3. Sand-deflectors 4 are secured to the bottom of the tank inside, and between the entering heads 5 and 6 of the jet tubes. The sand-deflectors 45 are hollow, gable-ended angle castings arranged with their ridges upward. Their office is to deflect the falling sand into the water jets, thus preventing any accumulation of sand in the bottom of the tank between or 50 about the jet orifices.

The inclined and curved vanes 7 are secured on the main wings or deflectors 8. The vanes and wings curve upwardly and out-

wardly from the partition 9 of the tank and the vanes follow the surface of the wings to 55 which they are attached, and, in addition, the vanes 7 possess a forward inclination. That is to say, they slant upwardly and toward the end of the tank opposite to that at which the sand enters the tank. In my invention the sand is served to the tank at the left hand and beyond the wings. The wings are attached to yokes 10 and 11, and above the yokes are bridges 12 and 13 provided with threaded blocks 14 and 15 through 60 which pass the screw rods 16 and 17, the lower ends of the rods being coupled with the yokes and their upper ends being furnished with the hand wheels 18 and 19 as shown.

As in my former invention hereinbefore referred to, the sides of the tank are usually inclined, and upon them are held the amalgamating plates 20, of any shape or type desired.

It is shown in Figs. 2 and 3 that the head 5 75 of the jet tube 2 is constructed with the slot mouths 21 and 22, and these mouths are arranged one on each side of the vertical partition *a* of the tank. As ordinarily formed, the head 5 is threaded and engages a corresponding orifice in the bottom of the tank, and when screwed up so as to bring the flanges of the head against the tank, the slot mouths are arranged as stated, one on each side of the partition 9. This method of construction also brings tops of the jet heads 5 and 6 flush with the inner surface of the tank bottom, and the descending sand passes along the surface directly into the ascending water jets, but in the event it is desired to use manganese steel or phospher bronze or other hardened metals in the construction of said jets or such device as may be employed for conducting the material or water into the tank then any method may be used to secure the jet 80 without threading. Certain of the tubes 2 are constructed with the heads 6, in all respects similar to heads 5, but having the inclined slot mouths 23, as illustrated in Fig. 4. The tubes so constructed are placed in 85 the left hand portion of the tank. There are no wings or blades above them, and the inclined slot mouths are introduced to cause a regular movement of the sand and water toward the right. In the remaining portion of 90 the tank, that is to say, the greater length of

95 100 105

it toward the right hand end a straight jet or tube of any form or shape that will carry the material or water up against wings 8-8 is sufficient.

5 In Fig. 4 I have shown one means for securing the sand-deflectors 4 to the tank bottom, that is, by passing the screws 24 and 25 through the sand-deflectors into the tank bottom. Any convenient mode of effectually holding the sand-deflectors may be employed.

The discharge apertures of the tank are designated by numbers 26 and 27.

15 In the operation of my invention after the wings 8 have been raised or lowered into the position desired by means of the screw rods, the sand is served to the left hand end of the tank or up through the tubes as herein before described and water under pressure passes

20 from the main 1 upward through the jet or tubes. Before reaching the wings, the inclined slot mouths direct the jets of water slightly toward the right as set forth. The sand rises with the jets of water from the heads 6 and moves toward the wings. Portions of the sand and water spread outwardly and come into contact, while descending, with the amalgamating plates 20. The entire charge of sand is gradually but surely

25 worked to the right and comes beneath the wings which direct the flow outwardly to the plates 20. The heavy particles not taken up by the plates fall down the sides of the tank and by the sand-deflectors 4 are caused

30 to move directly upon the flush heads and into the upwardly moving streams of water from the slot mouths of the heads 5. By making the heads flush as stated no sand can accumulate about them, but is all acted

35 upon and sent upwardly next to partition 9 as described. As indicated by the arrows, the path of the sand and water is now modified by the blades 7 and the upward movement has impressed upon it a forward

40 motion, which may be diminished or increased by moving the adjusting bar 31. Thus the sand and water reach the plates 20 with a slightly forward tendency. The path

45 of the sand and water is, in fact, screw-form or spiral. The constant agitation separates the particles of gold from the sand, and, furthermore, those particles are cleaned and washed and rendered particularly susceptible to amalgamation by plates 20. By the

50 time that the forward movement caused by blades 7 has brought the sand and water to the outlets 26 and 27, practically every grain of the mixture has been for a time in contact with one or the other of plates 20, and substantially all the particles of gold caught up by those plates.

Having thus described my invention, and explained the mode of its operation, what I claim is:

65 1. In a gold washer or amalgamator the

combination with a tank, of deflecting wings, means constructed to adjust the said wings, blades attached to the said wings and adjustable, also water-serving and jet-forming devices fashioned and disposed to discharge 70 upwardly from the bottom of the tank toward the lower edges of the wings whereby the sand and water are deflected outwardly.

2. In a gold washer or amalgamator, the combination with a tank, of deflecting wings, means constructed to adjust the said wings, inclined blades attached to the said wings with adjustable inclination and water-serving and jet-forming devices fashioned and disposed to discharge upwardly from the bottom of the tank toward the lower edges of the wings whereby the sand and water are deflected outwardly. 75

3. In a gold washer, the combination with a tank divided by a vertical partition into 85 compartments, of deflecting wings arranged at the sides of the said partition, means constructed to adjust the said wings, vanes attached to the said wings, and water-serving and jet-forming devices fashioned and disposed to discharge upwardly from the bottom of the tank whereby the sand and water are directed upwardly to be deflected outwardly by the wings. 90

4. In a gold washer, the combination with 95 a tank divided by a vertical partition into compartments, of deflecting wings arranged at the sides of the said partition, means constructed to adjust the said wings, inclined vanes attached to the said wings, and water-serving and jet-forming devices fashioned and disposed to discharge upwardly from the bottom of the tank, whereby the sand and water are directed upwardly and then are deflected outwardly by the wings and forwardly by said vanes. 100

5. In a gold washer, the combination with a tank, of deflecting wings extending lengthwise within the tank, the said wings being less in length than the tank, means constructed to adjust the said wings, and water-serving and jet-forming devices fashioned and disposed to discharge directly upward from the bottom of the tank below said wings and toward the lower edges of the wings, and jet-forming devices having inclined mouths and arranged in that portion of the tank extending beyond the ends of the wings, whereby the sand and water are directed forwardly and upwardly and deflected outwardly by 115 said wings. 120

6. In a gold washer, the combination with a tank, of sand deflectors secured within the tank upon the bottom thereof, the said sand deflectors comprising inclined surfaces meeting and forming an edge at the top thereby affording no lodgment for descending particles, and jets arranged to discharge upwardly from the bottom of the tank, the inclined surfaces of adjacent sand-deflectors 125 130

converging downwardly toward the jets whereby falling particles are directed into each jet from both sides of the jet.

7. In a gold washer, the combination with 5 a tank constructed greater in length than in breadth, of sand-deflectors secured within the tank upon the bottom thereof in a row lengthwise of the tank, the said sand-deflectors comprising inclined surfaces meeting 10 and forming an edge at the top thereby affording no lodgment for descending particles, and jets arranged to discharge upwardly from the bottom of the tank, the inclined surfaces of adjacent sand-deflectors converging downwardly toward the jets whereby falling particles are directed into each jet from both sides of the jet.

8. In a gold washer, the combination with 20 a tank having downwardly converging sides, of sand-deflectors secured within the tank upon the bottom thereof in a row, the said sand-deflectors comprising inclined surfaces meeting and forming an edge at the top thereby affording no lodgment for descending particles, and jets arranged flush with the bottom of the tank and discharging upwardly 25 between the sand-deflectors, the converging surfaces of adjacent sand-deflectors being adapted to direct the falling particles into 30 each jet from both sides of the jet.

9. In a gold washer, the combination with a tank, of water-serving and jet-forming devices arranged to discharge upwardly within the tank, wings constructed and disposed to 35 deflect the sand and water outwardly, and vanes attached to the said wings and having adjustable portions adapted to deflect the outwardly-moving sand and water.

10. In a gold washer, the combination 40 with a tank, of water-serving and jet-forming devices arranged to discharge upwardly within the tank, wings constructed and disposed to deflect the sand and water outwardly, and inclined vanes attached to said 45 wings and having adjustable portions adapted to deflect the outwardly-moving sand and water.

11. In a gold washer, the combination 50 with a tank, of water-serving and jet-forming devices arranged to discharge upwardly within the tank, wings constructed and disposed to deflect the sand and water outwardly, vanes attached to the said wings and having adjustable portions adapted to 55 deflect the outwardly-moving sand and water, and mechanism constructed and arranged to adjust simultaneously the movable vane portions borne by each wing.

12. In a gold washer, the combination 60 with a tank, of water-serving and jet-forming devices arranged to discharge upwardly within the tank, wings constructed and disposed to deflect the sand and water outwardly, vanes attached to said wings and 65 having adjustably pivotal portions adapted

to deflect the outwardly-moving sand and water, and mechanism constructed and arranged to adjust simultaneously the movable vane portions borne by each wing.

13. In a gold washer, the combination 70 with a tank, of water-serving and jet-forming devices arranged to discharge upwardly within the tank, a deflector adapted to deflect the upwardly-flowing sand and water outwardly toward the sides of the tank, and 75 additional deflectors movably supported in the upper part of the tank and arranged breadthwise vertically to act upon the outwardly-flowing sand and water after it has been acted upon by the first mentioned deflector and to deflect the sand and water toward one end of the tank.

14. In a gold washer, the combination 80 with a tank, of water-serving and jet-forming devices arranged to discharge upwardly 85 in the tank, a movable partition, wings attached to the partition, and means for adjusting the said wings, the edge of the said partition being placed directly above the said jet-forming devices whereby the upwardly-moving sand and water is divided 90 and caused to pass on both sides of the partition.

15. In a gold washer, the combination 95 with a tank having sides inclining divergently upward, of a vertical partition arranged to divide the tank into chambers each having a vertical and an inclined side, water-serving and jet-forming devices disposed to discharge vertically next the said 100 partition and on both sides of it whereby gold-bearing sand in each chamber may be carried directly upward along the partition and then outwardly to the inclined sides, substantially as described.

16. In a gold washer, the combination 105 with a tank having a vertical partition, of water-serving and jet-forming devices disposed to discharge vertically next the said partition and on both sides of it, and deflecting wings arranged to project from the partition whereby gold-bearing sand that is carried directly upward along the partition is deflected outwardly to the sides of the tank, substantially as described.

17. In a gold washer, the combination 110 with a tank having a vertical partition, of water-serving and jet-forming devices disposed to discharge vertically next the said partition and on both sides of it, deflecting 115 wings arranged to project from said partition, and means for adjusting the said wings with respect to the said sides and partition, substantially as described.

In testimony whereof I affix my signature 120 in presence of two witnesses.

BENALIAH G. JAYNE.
